UNITED STATES PATENT OFFICE.

HEBER M. STUART, OF BALTIMORE, MARYLAND, ASSIGNOR TO ELECTROLYTIC ZINC COMPANY, INC., OF NEW YORK, N. Y., A CORPORATION OF NEW YORK.

METHOD OF HANDLING ANODES IN ELECTROLYTIC BATHS.

1,299,519.

Specification of Letters Patent.

Patented Apr. 8, 1919.

Application filed July 26, 1916. Serial No. 111,367.

To all whom it may concern:

Be it known that I, HEBER M. STUART, subject of the King of England, residing at 3102 O'Donnell street, Baltimore and State 5 of Maryland, have invented certain new and useful Improvements in Methods of Handling Anodes in Electrolytic Baths, of which the following is a specification.

This invention relates to a method of 10 handling anodes in electrolytic baths for the separation of metals and to devices for use in the practice of such method.

Objects of the invention are to prevent mechanical contamination of the slime from 15 the anode from reaching the cathode deposit; to cut down the percentage of slime produced; and to keep the slime product always in close contact with the remaining portion of the anode during the disintegration of the latter. Other objects and 20 aims of the invention will appear from the following description, reference being had to the accompanying drawing in which is illustrated a form of device which I have 25 found well adapted to the practice of my method.

In the drawing, Figure 1 is an elevation, with parts in section showing an anode with 30 my novel device in place; and Fig. 2 is a vertical section of the same.

Referring to the numerals on the drawing, 1 indicates an anode such as is used in the zinc refining process described in an application for Letters Patent of the United 35 States Serial No. 111,350 filed by Charles H. Aldrich and John K. Bryan; that is to say, the anode illustrated in the drawing comprises zinc-bearing material cast into anode form having lugs, one of which rests 40 upon the bus-bar 2 while the other lug rests upon the usual insulation 3; the body of the anode depending into the electrolytic tank or cell in the usual manner. As illustrated, 45 the anode is relatively thin in cross section, and it will be understood that the usual electrolyte is employed, for instance zinc sulfate. 4 indicates an envelop or bag of some suitable material as for instance duck or canvas which is pervious to the electrolyte, but through which the slimes, etc., resulting from the disintegration of the anode 50 will not pass. This bag is close fitting to start with, and it is tied at the top by any suitable means as for instance the loops 55 5. It will be appreciated that this close-fitting

bag will result in preventing mechanical contamination of the cathode deposit by the slime; and it will cut down the percentage of slimes produced, because the slime, being always in contact with the anode, continues 60 to act as part of the anode, and the zinc content of the slime continues to dissolve, due to electrolytic action. In order to maintain the tightness of fit of the bag as the disintegration of the anode proceeds under electrolysis, I place at suitable intervals along the depending length of the anode pairs of partition strips 6, of wood or the like, bound together at their ends so that they will remain in place. The result of this construction is to keep the bag close up to the in- 65 closed anode and to prevent the slimes from slipping to the bottom of the bag and causing a bulge, which is obviously objectionable particularly where, as in the usual practice, 70 the anode and cathode are in close side-by-side relation. Furthermore, where the strips of wood 6 press against the bag they constitute a current shield for the anode surface immediately thereunder, so that the anode 75 will disintegrate where it is not covered by the strips, and where it is covered by the strips ribs will be formed, so that the bag will constantly be stretched. The result accomplished by means of the strips 6 might 80 be obtained by painting upon the bag a band of suitable non-conducting material, such as non-conducting paint. Instead of arranging the current-shields or partition-strips 6 or their equivalents horizontally as shown in 85 the drawings, they might be vertically disposed or otherwise arranged.

In addition to the advantages which have been mentioned the presence of the bag results in keeping any impurities in the slime 95 in close contact with the excess metal (for instance, zinc) of which the anode is mainly composed, and which metal it is desired to deposit upon the cathode without co-deposition of any other metal. Thus in the zinc 100 process referred to the cadmium in the slime is prevented from going into solution by reason of the fact that the slime is always held in contact with the excess of zinc in the anode, cadmium being of course more electro- 105 negative than zinc.

The bag also assists in maintaining the integrity of the anode, except for the normal disintegration due to electrolysis. Thus the usual flaking off of the anode, and the drop- 110

ping of the flakes to the bottom of the cell are prevented.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense.

It is to be understood that the language used in the following claims is intended to cover all the generic and specific features of the invention herein described and all statements of the scope of the invention which, as a matter of language, might be said to fall therebetween.

I claim:

- 20 1. The method of handling a soluble anode in an electrolytic bath for the separation of metals, which consists in surrounding the anode with a closely fitting envelop of material pervious to the electrolyte but through which the slimes, etc., resulting from the disintegration of the anode will not pass and maintaining the tight fit of the envelop as disintegration of the anode proceeds.
- 25 2. The method of handling a soluble anode in an electrolytic bath for the separation of metals, which consists in causing electrolytic disintegration of distinct areas of the anode, and keeping the slimes from such disintegration segregated and in contact with the respective portions of the anode area from which they are produced.
- 30 3. The method of handling a soluble anode in an electrolytic bath for the separation of metals, which consists in protecting certain portions of the anode surface against electrolytic action, causing electrolytic action upon

the remaining surfaces, and keeping the slimes resulting from such electrolytic action segregated and in contact with the portions of the anode surface from which they are produced.

4. A soluble anode provided with a closely fitting envelop of material pervious to solution to be electrolyzed but through which the slimes, etc., resulting from the disintegration of the anode will not pass, and non-conducting current-shields on the envelop protecting the surfaces of the anode therebeneath from electrolytic action.

5. A soluble anode provided with a closely fitting envelop of material pervious to solution to be electrolyzed but through which the slimes, etc., resulting from the disintegration of the anode will not pass, and non-conducting current-shields on the envelop protecting the surfaces of the anode therebeneath from electrolytic action, said current-shields dividing the surface of the anode into distinct areas and bearing against the anode surface to prevent slimes produced from one area under electrolysis from passing to another area.

6. A soluble anode relatively thin in cross-section, and provided with a closely fitting envelop of material pervious to solution to be electrolyzed but through which the slimes, etc., resulting from the disintegration of the anode will not pass, and a pair of non-conducting strips, one on each side of the envelop, pressing the latter and the contained envelop between them.

In testimony whereof I affix my signature in presence of two witnesses.

HEBER M. STUART.
